CLAIM

The ornamental design for a hand-held exercise apparatus, as shown and described.

DESCRIPTION

FIG. 1 is a front perspective view of a hand-held exercise apparatus showing my new design;

FIG. 2 is a front elevation thereof, the rear elevation being identical to the view shown;

FIG. 3 is a right side elevation thereof, the opposite side elevation being identical to the view shown; and,

FIG. 4 is a top plan view thereof, the bottom plan view being identical to the view shown.

FIG. 1

FIG. 2

FIG.3
